C. BOOZE.

WALL PAPER.

No. 20,218.

Patented Oct. 21, 1890.

UNITED STATES PATENT OFFICE.

CHARLES BOOZE, OF BUFFALO, NEW YORK, ASSIGNOR TO M. H. BIRGE
& SONS, OF SAME PLACE.

DESIGN FOR WALL-PAPER.

SPECIFICATION forming part of Design No. 20,218, dated October 21, 1890.

Application filed September 27, 1890. Serial No. 366,371. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying photograph, forming part thereof.

- 10 The leading feature of my design consists of disconnected branches of flowers and leaves of the jasmine running lengthwise in graceful curves under and over upright stencil ornaments, the upper portions of which are in-
15 closed in ornamental panels formed by intersecting semicircular lines arranged horizontally above the upright ornaments, as represented in the accompanying photograph. The semicircular lines form a horizontal scal-
20lop above the upright stencil ornaments, and

at their points of intersection between the upright ornaments they continue downwardly and their ends are connected by curved lines with the upright stencil ornaments to form the panels which inclose the upper portions 25 of the upright ornaments. A narrow horizontal band extends across the top, and two parallel lines are arranged horizontally along the bottom.

My design is more particularly designed for 30 and used as a ceiling decoration or border.

What I claim is—

The design for wall-paper herein shown and described.

Witness my hand this 13th day of September, 1890.

CHARLES BOOZE.
